SAFETY LOWERING DEVICE

Clarence H. Sherbrook and Leonard F. Nolley,
Flint, Mich.

Application May 6, 1947, Serial No. 746,192

1 Claim. (Cl. 254—160)

1 This invention relates to improvements in devices for safely lowering heavy objects or persons and more particularly to an improved device adapted to be secured in a window or other opening in a building wall at an upper floor level to serve as a fire escape so that a person trapped on an upper floor of a building during a fire in the building may be safely lowered to the ground. The device is capable however of other uses and may be used for various other purposes without in any way exceeding the scope of the invention.

It is among the objects of the invention to provide an improved safety lowering device which is simple in construction, economical to manufacture, easy to install in a building wall opening such as a window opening, is of adequate strength to lower an object of the weight of a heavy person safely from an upper floor level of a building to the ground, is continuous in operation so that several persons may be lowered one after the other by use of the device, and which is smooth and positive in operation without any tendency to bind or slip at any time.

Other objects and advantages will become apparent from the following description in conjunction with the accompanying drawings wherein:

Fig. 1 is an elevational view of a safety lowering device illustrative of the invention;

Fig. 2 is a view similar to Fig. 1 showing the operating components of the device in longitudinal cross section;

Fig. 3 is a transverse sectional view on an enlarged scale on the line 3—3 of Fig. 1; and,

Fig. 4 is an elevational view showing the improved safety lowering device in operative position in a window opening of a building.

With continued reference to the drawings, the numeral 10 generally designates a rectangular frame having a top member 11, a bottom member 12 and side members 13 and 14. A pair of brackets 15 and 16 are secured to the inner surface of the bottom member 12 and have leg portions extending inwardly substantially parallel to the vertical center line of the frame and spaced from each other. A pair of shafts 17 and 18 are rotatably mounted in the lower end portion of the frame each having its outer end journalled in a suitable respective bearing, as indicated at 19 and 20, secured in the corresponding side frame members 13 and 14, and its inner end extending through an aperture in the outer end of the inwardly extending leg portion of the corresponding bracket 15 or 16. The two

shafts 17 and 18 are in axial alignment with each other and are connected at their inner ends by a crank 21 to constitute a crankshaft, the pin of which is pivotally connected to the lower end of a piston rod 22 which extends through the bottom end of a cylinder 23 and carries a piston 24 at its upper end which piston is reciprocable in the cylinder.

The upper end of the cylinder 23 is secured to a transverse shaft 25 the ends of which are journalled in inwardly projecting leg portions of angle brackets 26 and 27 secured to the under surface of the top member 11.

A filler cap 28 is provided in the top end wall 15 of the cylinder and the upper and lower end portions of the cylinder are connected by a restricted passage provided in an external longitudinal tube 29 the ends of which are hydraulically connected with the interior of the cylinder 23 adjacent the opposite end walls thereof.

If desired, a valve screw 30 may be applied to the tube 29 in a manner to adjustably restrict the passage therethrough to control the speed of operation of the device, and the piston 24 may also be provided with small apertures 31 extending therethrough to permit an extremely slow operation of the device in case the tube 29 is entirely closed off. A packing gland 32 surrounds the piston rod 22 at the bottom end 30 of the cylinder to prevent leakage of fluid from the cylinder where the rod passes through the lower end wall of the cylinder.

A spool or drum 33 is rotatably mounted on the shaft 17 and has a rope or cable 34 wound thereon and depending from the device, and a similar spool or drum 35 is rotatably mounted on the shaft 18 and has a rope or cable 36 wound thereon. A spacer 37 is disposed between the inwardly projecting leg of the bracket 15 and the adjacent end of spool 33 and a similar spacer 38 is disposed between the spool 35 and the inwardly projecting leg of bracket 16.

Ratchet means are provided to rotationally lock the cable drums to the respective crankshaft end portions for one direction of rotation. A convenient ratchet mechanism may comprise a dog 39 mounted on the outer end surface of the drum, a transverse pin 40 extending through a somewhat elongated aperture in the shaft, a washer 41 surrounding the shaft adjacent the pin and a compression spring 42 surrounding the shaft between the washer and the adjacent inner surface of the frame side member. The dog 39 has an inclined top surface and a notched end to receive the pin so that the drum may

rotate on the shaft in one direction, the inclined surface of the dog forcing the pin away from the drum so that the dog will pass under the pin. When the drum is rotated in the opposite direction the notched end of the dog will engage the pin and force the shaft to rotate with the drum. As the ratchet mechanism is the same for both drums a detailed description of only one is considered sufficient for the purposes of this disclosure.

Respective line levelling devices 43 and 44 are provided for the cables 34 and 36 and are preferably mounted on the side edge of the bottom member 12 immediately below the corresponding spools or drums 33 and 35. The two levelling devices are similar in construction and each may comprise a rotatable shaft 45 having opposite screw threads thereon and mounted at its end in journal blocks 46 and 47 secured to the frame. The shaft is driven from the inner end flange by a suitable gear train 48 and carries a sleeve 49 which is movable from one end of the shaft to the other and has its direction reversed at each end of the shaft in the conventional manner. A cable engaging hook or loop 50 is carried by the sleeve to lay the cable smoothly onto the drum.

The operation of the device is believed to be readily apparent from the drawing and the above description.

As shown in Fig. 4 the frame 10 is mounted in the upper part of a window opening 51 by suitable means such as cap screws 52 passing through the upper frame member 11 and into the window lintel 53. When it is desired to lower an object or person from the window the end of one of the cables 34 or 36 is attached to the object or grasped by the person and the person or object suspended from the cable. The cable will then unwind from the corresponding spool 33 or 35 and the hydraulic brake mechanism, including the piston rod 22, piston 24 and cylinder 23, will operate to control the rate at which the cable unwinds from the drum. The rate of descent can be so regulated that a person or object will be lowered from the window opening to the ground level without danger of injury.

When one cable has been unwound from the corresponding drum an object may be attached to the other cable, or the other cable may be grasped by a person desiring to descend from the window, and as this second cable is unwound from its associated drum the other cable will be rewound on its drum, the cables being wound in opposite directions on the corresponding drums. By this means, as soon as the second cable has been unwound the first cable will have been completely rewound and is in condition for further use so that another object or person may be

lowered from the window opening. The device may thus continue in operation as long as may be necessary or desired.

When the operation of the device has been completed at least one of the cables will be left in an unwound condition and this cable may then be manually rewound by rotating the corresponding spool on its respective shaft, the ratchet connection between the spool and the shaft permitting rotation of the spool in the proper direction to rewind the cable without operating the hydraulic mechanism.

The invention may be embodied in other specific forms without departing from the spirit or essential characteristics thereof. The present embodiment is therefore to be considered in all respects as illustrative and not restrictive, the scope of the invention being indicated by the appended claim rather than by the foregoing description, and all changes which come within the meaning and range of equivalency of the claim are therefore intended to be embraced therein.

What is claimed is:

A safety lowering device comprising a rectangular frame; a crank shaft journaled at its ends in said frame; a pair of cable drums on said shaft, disposed one at each side of the crank; a cable on each drum, said cables being oppositely wound; hydraulic brake means operatively connected between said crank and said frame to control the speed of rotation of said drums when said cables are being unwound therefrom; and a respective one-way drive ratchet connection between each drum and said crankshaft whereby said cables may be rewound on said drums without operating said hydraulic brake means, each such one-way drive ratchet connection comprises an inclined dog secured on the outer end space of the corresponding cable drum, a pin extending through an elongated transverse aperture in said crankshaft, a washer bearing against said pin and a coiled compression spring surrounding said crankshaft between said washer, and the adjacent inner surface of said frame.
